PRESSER MECHANISMS FOR SEWING MACHINES

Anthony J. Matuzas, Union, N.J., assignor to The Singer Manufacturing Company, Elizabeth, N.J., a corporation of New Jersey

Application August 1, 1956, Serial No. 601,546

9 Claims. (Cl. 112—236)

This application is a continuation in part of application Serial No. 541,943, filed October 21, 1955, which has been abandoned in favor of the present application.

The present invention relates to presser mechanisms for sewing machines and more particularly to a so-called quick-adjustment device for sewing machine presser mechanisms, i.e., a device by means of which the compression of the spring that biases the presser bar toward the work-supporting surface may be conveniently released to permit work such as darning that does not require a feeding of the work and therefore does not require a strong presser action, and may be conveniently restored for normal sewing or set at a number of intermediate positions of adjustment as required for sewing different materials.

The primary object of the present invention is to provide a quick-adjustment device for a sewing machine presser mechanism that has a simplified actuation thus being convenient and easy to operate. Further objects of the present invention are to provide a presser quick-adjustment device that is inexpensive, can be readily assembled and disassembled for initial assembly or repair or replacement of parts, is durable and dependable in operation, can be used on existing machines, and is neat and attractive.

Having in mind the above and other objects that will be evident from an understanding of this disclosure, the invention comprises the devices, combinations and arrangements of parts as illustrated in the presently preferred embodiment of the invention which is hereinafter set forth in such detail as to enable those skilled in the art readily to understand the function, operation, construction and advantages of it when read in conjunction with the accompanying drawings in which:

Fig. 1 is a fragmentary head and elevational view with a portion in section of a sewing machine embodying the present invention.

Fig. 2 is a detail sectional view taken substantially on the line 2—2 of Fig. 1.

Fig. 3 is an exploded perspective view of the quick-release device per se.

Figs. 4, 5 and 6 are fragmentary detail sectional views illustrating various positions in the actuation of the device.

Fig. 7 is a view similar to Fig. 1 but illustrating a modification of the invention.

Fig. 8 is a detail section view taken substantially on the line 8—8 of Fig. 7.

Fig. 9 is a detail section view similar to Fig. 8 but illustrating the parts in a different position of adjustment.

Fig. 10 is an exploded perspective view of the parts per se of the modified quick-adjustment device as illustrated in Fig. 7.

With reference to the drawings, the present invention is illustrated as embodied in a sewing machine having a frame including a head 1 and bed 2 having a throat plate 3. The presser mechanism, which is designed to hold the work down against the throat plate 3 and feed-dogs 4 of

the feeding mechanism, comprises a short hollow presser-bar 5 mounted for longitudinal sliding movement in a bushing 6 in the head 1, and carrying a presser foot 7 at its lower end. The presser bar 5 has an axial bore 8 extending longitudinally from the upper end and in which is disposed a coiled compression spring 9 that bears at its lower end against the bottom of the bore 8. At its upper end, the spring 9 abuts against a compression rod 10, the lower end of which telescopes into the bore 8. Extending longitudinally into the upper end of the connecting rod 10 is a small axial guide bore 11 that receives a pin 12 which consists of the reduced diameter lower end of a rod 13. The rod 13 is mounted for axial sliding movement in the bore 14 of an externally threaded bushing 15 screwed into the head 1.

There is provided a releasable latch means between the rod 13 and the bushing 15 for holding the rod 13 down against the action of the spring 9 and thus for holding the spring 9 in compression, the latch means being designed to permit free sliding movement of the rod 13 downwardly relatively to the bushing 15 or in the direction to increase the action of the spring 9 and for releasably latching the rod 13 against movement in the opposite direction. Toward this end, the upper end of the bushing 15 is provided with internal threads which cooperate with external threads upon the upper end of a sleeve 16 disposed in the bore 14 to secure the sleeve 16 in the bore 14. The sleeve 16 is provided with a screw driver slot 17 to facilitate tightening. The lower end of the sleeve 16 is formed of spring or tool steel and is longitudinally slotted inwardly from its lower end to form spring fingers 18 which in effect constitute a plurality of leaf springs arranged longitudinally of the rod 13. The lower or free ends 19 of the leaf springs or spring fingers 18 are turned inwardly toward the axis of the sleeve to engage the periphery of the rod 13. The rod 13 has a reduced-diameter portion 20 near its lower end to form a stop-shoulder 21 and has a second reduced portion 22 spaced from the reduced portion 20 to define a cam-collar 23 between the two reduced portions. The lower face of the cam-collar 23 is inclined with respect to the axis of the rod 13 to define a cam surface 24 while the upper face of the cam-collar is normal to the rod to define a stop surface 25. Slidably mounted on the reduced portion 22 is a collar 26 that is somewhat less in length than the length of the reduced portion 22 so that it is free to slide to a limited extent between the stop 25 and a stop shoulder 27 at the upper end of the reduced portion 22.

The upper end of the rod 13 is expanded by means of a thumb screw 28 to facilitate manual depression of the rod 13 against the action of the spring 9.

As a manufacturing expedient, the rod 13 may be made in two parts separated along the line 29, Fig. 2, and press-fitted together after the collar 26 has been placed on the reduced portion 22, and the pin 12 may be press-fitted into a bore in the end of the lower part of the rod 13, as indicated at 30, rather than being integral. In addition, the sleeve 16 may be made in two parts comprising the upper threaded part and a cylinder including the spring fingers 18, the parts being brazed together.

To assemble the parts, the sleeve 16 is screwed into the bore of the bushing 15 and the rod 13 is pushed through the sleeve from the upper end so that the free ends 19 of the spring fingers 18 will be deflected over the lower end of the rod 13 onto the reduced portion 20. The assembly is then inserted into the machine by screwing the bushing 15 into the head 1. It will, of course, be obvious that this device can be used in existing machines by designing the bushing 15 to be substituted for the usual presser bar spring abutment bushing of the machine.

In operation, the normal operative position of the

parts is illustrated in Fig. 2. In this position, the ends 19 of the spring fingers 18 engage the stop 25 on the rod 13 to hold the rod against the action of the spring 9 and thus hold the spring 9 in compression. The compression of the spring 9 can be adjusted by screwing down or backing off the bushing 15 in the head 1. To release the compression of the spring 9, the rod 13 is pushed down into the position illustrated in Fig. 4 in which position the collar 26 is moved into engagement with the stop 27 and the ends 19 of the spring fingers 18 are deflected onto the collar 26. When the rod 13 is released, the spring 9 urges it up, with the ends 19 of the spring fingers 18 resiliently gripping the periphery of the collar 26 so that as the rod 13 moves up under the action of the spring 9, the collar 26 will be held stationary and the rod 13 moves relative thereto until the collar is engaged by the stop 25 as illustrated in Fig. 5. As the rod 13 continues to move up, the collar 26 is carried with it and the ends 19 of the spring fingers 18 slide off the collar. Since the diameter of the collar 26 is made equal to or larger than the diameter of the stop 25, the ends 19 of the spring fingers 18 will, in effect, be lifted over the stop 25 and slide off the collar 26 onto the cam face 24 and onto the reduced portion 20, and finally into contact with the stop 21 as illustrated in Fig. 6. When engaged against the stop 21, the ends 19 of the spring fingers 18 hold the rod 13 against further sliding movement to prevent any further expansion of the spring 9. The stop 21 is positioned so that there will be only a light compression of the spring 9, or in other words, the compression of the spring 9 is relaxed so that there is only a light pressure urging the presser foot 7 against the throat plate 3. To restore the normal sewing condition, the rod 13 is depressed to compress the spring 9, the spring fingers 18 being deflected over the cam-collar 23 by the cam face 24 to engage the stop 25, the collar 26 being freely slidable away from the stop 25.

In Figs. 7-10 there is illustrated a modification of the invention which includes a plurality of intermediate positions of adjustment. In this construction, there is provided a rod 31 which is comparable to the rod 13 of the embodiment of the invention disclosed in Figs. 1-6. The rod 31 is mounted for axial sliding movement in the bore 32 of an externally threaded bushing 33 screwed into the head 1. The upper end of the bushing 33 is provided with internal threads which cooperate with external threads upon the upper end of a tubular spring or spring sleeve 34 disposed in the bore 32 to secure the sleeve 34 in the bore 32. The sleeve 34 is the same as the sleeve 16 and includes the spring fingers 35 which are comparable to the spring fingers 18.

Intermediate its ends the rod 31 is grooved to provide a plurality of collars 36 spaced axially along the rod, each of said collars 36 having a lower edge that is inclined relative to the axis of the rod, thus defining a cam surface 37 that is adapted to deflect the ends of the spring fingers 35 as the rod 31 is lowered relative to the spring fingers so that the fingers 35 will ride freely thereover, and a flat upper face that is normal to the axis of the rod 31, thus defining a stop shoulder 38 against which the lower edges of the fingers 35 will engage to prevent upward movement of the rod relative to the fingers 35. To release the spring fingers 35 from operative relation with respect to the stop shoulders 38, there is provided a releasing sleeve 39 surrounding the rod 31 internally of the spring sleeve 34 and slideable axially relative to the rod 31 and spring sleeve 34. A coil spring 40 seated in an axial bore 41 in the top of the spring sleeve 34 bears against the underside of a head 42 on the releasing sleeve 39 to bias the sleeve 39 upwardly to a normal position as illustrated in Fig. 8 in which the lower end thereof is out of engagement with the spring fingers 35 and the spring fingers 35 are in operative engagement with one of the stop shoulders 38. The rod 31 is nor-

mally held against rising under the action of the presser bar spring 9 and holds the spring 9 under a predetermined compression. When the releasing sleeve 39 is forced downwardly, as by manual pressure on the head 42, the ends of the spring finger 35 will be cammed outwardly out of operative relation with the stop shoulders 38, as illustrated in Fig. 9. The rod 31 is thus free to rise under the action of the presser bar spring 9 and it will spring up to a predetermined stop position that has been set in accordance with the minimum desired pressure and thereby reduce the compression of the presser bar spring 9. As illustrated in Fig. 9, this stop position is determined by a collar 43 held on the rod 29 by a snap ring 44, which collar 43 abuts against the bottom of the bushing 33. The snap ring 44 is seated in one of a plurality of circumferential grooves 45 in the periphery of the rod 31. The selection of the groove 45 as well as the adjustment of the bushing 33 will effect an adjustment of the minimum presser bar spring pressure obtainable.

After the releasing sleeve 39 has been depressed and the rod 31 has sprung up to the position illustrated in Fig. 9, the rod 31 may then be manually forced downwardly to place the presser bar spring 9 under increasing pressure during which time the ends of the spring fingers 35, by virtue of the cam surfaces 37, will ride freely over the collars 36. The rod 31 is provided with a head 46 which facilitates forcing it downwardly as well as prevents the releasing sleeve 39 from coming off the rod.

When the desired compression is obtained, if desired, which may be shown by suitable indicia (not shown), the rod 31 is released and the ends of the spring fingers 35 will engage with the adjacent stop shoulder 38 and will hold the rod 31 in the adjusted position.

Numerous other modifications of the structure herein disclosed will suggest themselves to those skilled in the art. However, it is to be understood that the present disclosure relates to a preferred embodiment of my invention which is for the purposes of illustration only and not to be construed as a limitation of the invention. All such modifications which do not depart from the spirit of the invention are intended to be included within the scope of the appended claims.

Having thus set forth the nature of the invention, what I claim herein is:

1. In a sewing machine having a frame, a presser bar mounted in said frame for longitudinal sliding movement, a spring for biasing said presser bar longitudinally, an adjustable abutment for said spring comprising an externally threaded bushing screwed into said frame and having a bore, and operative connections between said bushing and said spring including a quick-adjustment device comprising a rod mounted for axial sliding movement in the bore of said bushing and operatively connected to said spring for holding said spring under compression and to increase the compression of said spring upon axial movement of said rod in one direction and to reduce the compression of said spring upon axial movement of said rod in the other direction, and means for operatively connecting said rod to said bushing for permitting free sliding movement of said rod relative to said bushing in the direction to increase the action of said spring and for latching said rod against movement in the opposite direction after said rod has been moved beyond a predetermined point and for releasing said rod for free sliding movement in the direction to reduce the action of said spring upon continued movement of said rod beyond said predetermined point.

2. In a sewing machine having a frame, a presser bar mounted in said frame for longitudinal sliding movement, a spring for biasing said presser bar longitudinally, an adjustable abutment for said spring comprising an externally threaded bushing screwed into said frame and having a bore, and operative connections between said bushing and said spring including a quick-adjustment de-

vice comprising a rod mounted for axial sliding movement in the bore of said bushing and operatively connected to said spring for holding said spring under compression and to increase the compression of said spring upon axial movement of said rod in one direction and to reduce the compression of said spring upon axial movement of said rod in the other direction, and means including an actuating spring for operatively connecting said rod to said bushing for free sliding movement of said rod relative to said bushing in the direction to increase the action of said spring and for releasably latching said rod in a predetermined position against sliding movement in the opposite direction and for releasing said rod for free sliding movement in the direction to reduce the action of said spring upon axial movement of said rod beyond said predetermined position.

3. A quick-adjustment device for the presser mechanism of a sewing machine comprising a bushing adapted to be secured in the head of a sewing machine and having a bore, a sleeve secured in the bore of said bushing and having spring fingers disposed longitudinally of said bore, the free ends of said spring fingers being resiliently biased inwardly toward the axis of said sleeve, a rod mounted in said sleeve for axial sliding movement, a stop on said rod, said stop being formed to slide freely past said spring fingers as said rod is moved in one direction and to engage against said stop as said rod is moved in the other direction, a collar mounted for sliding movement on said rod and disposed to slide into engagement with said stop, and means for limiting the sliding movement of said collar away from said stop to a position in which the adjacent end of said collar is spaced from said stop, said collar having a cross section substantially equal to the cross section of said stop whereby said spring fingers can slide freely from said collar onto and over said stop when said collar is in engagement with said stop.

4. In a sewing machine having a frame, a presser bar mounted in said frame for longitudinal sliding movement, a spring for biasing said presser bar longitudinally, an adjustable abutment for said spring comprising an externally threaded bushing screwed into said frame for axial adjustment and having a bore, and operative connections between said bushing and said spring including a quick-adjustment device comprising a rod mounted for axial sliding movement in the bore of said bushing and operatively connected to said spring for holding said spring under compression, and releasable latch means operatively connecting said rod to said bushing comprising a spring finger carried by said bushing and arranged longitudinally of said rod with the end thereof biased into engagement with the peripheral surface of said rod, a stop shoulder on said rod, said stop shoulder being adapted to slide freely past the end of said spring finger when said rod is moved in the direction to increase the compression of said spring and to latch against the end of said spring finger as it is moved past the same when said rod is moved in the opposite direction, and means for moving the end of said spring finger out of operative relation with said stop shoulder to permit free sliding movement of said rod in said opposite direction.

5. A quick-adjustment device for a sewing machine comprising an externally threaded bushing adapted to be screwed into the head of a sewing machine and having an axial bore therethrough, a rod mounted for axial sliding movement in the bore of said bushing and adapted to be connected to the presser bar spring of the machine to hold the same under compression, and releasable latch means operatively connecting said rod to said bushing comprising a spring sleeve carried by said bushing within the bore thereof and surrounding said rod, said spring sleeve being slotted longitudinally to define a plurality of spring fingers arranged longitudinally of said rod with the ends thereof biased into engagement with the peripheral surface of said rod, a stop shoulder on said rod, said stop shoulder being adapted to slide freely past the ends

of said spring fingers when said rod is moved in the direction to increase the compression of the presser bar spring and to latch against the ends of said spring fingers as it is moved past the same when said rod is moved in the opposite direction, and means for moving the ends of said spring fingers out of operative relation with said stop shoulder to permit free sliding movement of said rod in said opposite direction.

6. A quick-adjustment device for a sewing machine comprising an externally threaded bushing adapted to be screwed into the head of a sewing machine and having an axial bore therethrough, a rod mounted for axial sliding movement in the bore of said bushing and adapted to be connected to the presser bar spring of the machine to hold the same under compression, and releasable latch means operatively connecting said rod to said bushing comprising a spring sleeve carried by said bushing within the bore thereof and surrounding said rod, said spring sleeve being slotted longitudinally to define a plurality of spring fingers arranged longitudinally of said rod with the ends thereof biased into engagement with the peripheral surface of said rod, a stop shoulder on said rod, said stop shoulder being adapted to slide freely past the ends of said spring fingers when said rod is moved in the direction to increase the compression of the presser bar spring and to latch against the ends of said spring fingers as it is moved past the same when said rod is moved in the opposite direction, and a releasing sleeve surrounding said rod and arranged internally of said spring sleeve, said releasing sleeve being slidable longitudinally of said rod to cam said spring fingers out of operative relation with said stop shoulder to permit free sliding movement of said rod in said opposite direction.

7. A quick-adjustment device for a sewing machine comprising an externally threaded bushing adapted to be screwed into the head of a sewing machine and having an axial bore therethrough, a rod mounted for axial sliding movement in the bore of said bushing and adapted to be connected to the presser bar spring of the machine to hold the same under compression, and releasable latch means operatively connecting said rod to said bushing comprising a spring sleeve carried by said bushing within the bore thereof and surrounding said rod, said spring sleeve being slotted longitudinally to define a plurality of spring fingers arranged longitudinally of said rod with the ends thereof biased into engagement with the peripheral surface of said rod, a plurality of stop shoulders spaced axially on said rod, said stop shoulders being adapted to slide freely past the ends of said spring fingers when said rod is moved in the direction to increase the compression of the presser bar spring and to latch against the ends of said spring fingers as it is moved past the same when said rod is moved in the opposite direction, and means for moving the ends of said spring fingers out of operative relation with said stop shoulders to permit free sliding movement of said rod in said opposite direction.

8. A quick-adjustment device for a sewing machine comprising an externally threaded bushing adapted to be screwed into the head of a sewing machine and having an axial bore therethrough, a rod mounted for axial sliding movement in the bore of said bushing and adapted to be connected to the presser bar spring of the machine to hold the same under compression, and releasable latch means operatively connecting said rod to said bushing comprising a spring sleeve carried by said bushing within the bore thereof and surrounding said rod, said spring sleeve being slotted longitudinally to define a plurality of spring fingers arranged longitudinally of said rod with the ends thereof biased into engagement with the peripheral surface of said rod, a plurality of stop shoulders spaced axially on said rod, said stop shoulders being adapted to slide freely past the ends of said spring fingers when said rod is moved in the direction to increase the compression of the presser bar spring and to latch against

the ends of said spring fingers as it is moved past the same when said rod is moved in the opposite direction, and a releasing sleeve surrounding said rod and arranged internally of said spring sleeve, said releasing sleeve being slidable longitudinally of said rod to cam said spring fingers out of operative relation with said stop shoulder to permit free sliding movement of said rod in said opposite direction.

9. A quick-adjustment device for the presser mechanism of a sewing machine comprising a bushing adapted to be secured in the head of a sewing machine and having a bore, a sleeve secured in the bore of said bushing and having spring fingers disposed longitudinally of said bore, the free ends of said spring fingers being resiliently biased inwardly toward the axis of said sleeve, a rod mounted in 10 said sleeve for axial sliding movement, a stop on said

rod, said stop being formed to slide freely past said

spring fingers as said rod is moved in one direction and

to engage against said stop as said rod is moved in the

other direction, and means for moving the ends of said

spring fingers out of operative relation with said stop to

permit free sliding movement of said rod in said other

direction.

15

rod, said stop being formed to slide freely past said spring fingers as said rod is moved in one direction and to engage against said stop as said rod is moved in the other direction, and means for moving the ends of said spring fingers out of operative relation with said stop to permit free sliding movement of said rod in said other direction.
